UNITED STATES PATENT OFFICE.

WILLIAM LINDSAY, OF CHICAGO, ILLINOIS.

SOUND-REPRODUCER.

1,285,258.

Specification of Letters Patent. Patented Nov. 19, 1918.

Application filed December 31, 1917. Serial No. 209,783.

To all whom it may concern:

Be it known that I, WILLIAM LINDSAY, a citizen of the United States, residing at Chicago, in the county of Cook and State 5 of Illinois, have invented certain new and useful Improvements in Sound-Reproducers, of which the following is a description, reference being had to the accompanying drawings, forming a part of this specification, in 10 which corresponding numerals of reference in the different figures indicate like parts.

The object of my invention is to provide a sound reproducer for use upon phonographs which, in addition to cheapness and simplicity of construction, shall have its elements so arranged and combined as to adapt themselves to accurate adjustment in such a way as to take up all lost motion while at the same time insuring the maximum delicacy, sensitiveness and freedom of action in the several movable parts, and that notwithstanding ordinary imperfections of construction. To these ends my invention consists in the combination of elements hereinafter 25 more particularly described and definitely pointed out in the claims.

In the drawings,

Figure 1 indicates a face view of a reproducer embodying the features of my invention,

Fig. 2, an edge view thereof,

Fig. 3, is an enlarged view of a portion of said reproducer taken upon the line 3—3, Fig. 1, viewed in the direction of the arrows 30 there shown, a portion being in section,

Fig. 4, is a plan view of a portion of the stylus lever and the cross-bar by which it is supported,

Fig. 5, is a detail view in plan of the 40 grooved end of the screw controlled adjusting member,

Fig. 6, is a like view of said member showing a ball as it would appear when resting in the groove, and

Fig. 7, an enlarged bottom view of one of the bearing extensions or arms of the bracket.

Referring to the drawings, 1 indicates the casing of an ordinary reproducer, 2 the diaphragm secured in place in any approved way, and 3 the usual stylus-lever having its long arm attached to the diaphragm at 4 and its short arm 5 provided with the usual set-screw 6 for securing the stylus 7 in place. 55 Formed upon or rigidly attached to the stylus-lever is a fulcrum-member or cross-

bar 8, provided near its ends and preferably upon its upper face, with transverse grooves 9, 9, and upon its lower face midway between the ends with a like groove 10, Fig. 3. The 60 grooves 9 are so formed as to cut through to an equal extent, a horizontal plane indicated by the dotted line 11—11, which I term the axial line or line of oscillation, while the groove or notch 10 is faced or extended in 65 a reverse direction and to a corresponding extent past said line.

A bracket, generally designated by 12, is rigidly attached to the casing 1 by means of screws 13, said bracket serving primarily as 70 a pivotal support for the fulcrum member 8. The middle portion of said bracket is removed to provide an opening for the reception of the fulcrum bar. Inwardly extended members or portions 14, are formed 75 upon said bracket in the ends of which are located longitudinal grooves 15, Figs. 3 and 7. The bracket 12 being in the same plane with the fulcrum bar 8, it follows that the line of the meeting faces of the grooves 15 80 will lie in the plane of the axis of said arm and at intersecting angles, preferably of ninety degrees, to the notches 9 with which the parts 14 are in registration.

An adjusting-screw 16, is tapped into the 85 bracket 12, and extended upwardly therein, as shown in Fig. 3; said screw being secured in place by means of a lock-nut 17. The upper end of said screw is adapted to contact with the lower end of a movable member 90 or block 18, Figs. 3, 5 and 6, which is accurately but slidably fitted into a bore in said bracket. A spline 19, attached to said member and fitted to slide in a groove in the bracket, serves to prevent rotation of the 95 member. The upper end of the adjusting member 18, has a groove 20 formed therein which corresponds to and is in the same plane with, the grooves 15 in the parts 14, except that it faces in an opposite direction. 100 The part 18 is in registration with the groove 10 and the groove 20 in said part is, in the example illustrated, arranged at right angles to the groove 10.

Balls 21, 21, preferably of bronze or 105 hardened steel, are placed between the fulcrum member and the extensions 14, so as to lie in the grooves 9, and extend upwardly into the grooves 15, arranged at right angles thereto in the extensions 14. 110 A like ball 22, is placed in the groove 20 of the adjustable member 18, so as to ex-

2

tend into and contact with the inclined walls of the groove 10, of the fulcrum-member. When the screw 16, is properly adjusted, the member 18, the ball 22 and the fulcrum member 8, will have been pushed upwardly until the balls 21 are in contact with the oppositely inclined faces of the grooves 15, in the opposing members 14 and 18, and when it is apparent that such result is accomplished and it is certain that there is no play or lost motion between the counterpart members and the balls, the adjustment will be complete and may be made permanent by means of the lock-nut 17.

15 It is obvious that the opposing grooves should be placed at opposing or intersecting angles, preferably right angles with respect to each other, in order to prevent the balls from falling out. This arrangement, however, performs a more important function in that it enables the balls automatically to adjust themselves to positions and to provide for a relatively considerable degree of imperfection in adjustment and construction of the parts. For example, if, in lieu of the opposing longitudinal and transverse notches, sockets were formed in the opposing members to fit the balls, a failure in registration of said sockets or a slight bending, or warping of the stylus lever, a slight lateral misplacement in its connection with the diaphragm, or a warping of the fulcrum member, or inaccurate workmanship, would cause friction or binding which would interfere with the free movement of the stylus lever and to that extent, interfere with the desired result, viz. a perfectly free movement of said lever without any lost motion.

40 Inasmuch as each ball is free to roll lengthwise of each groove until it is arrested by contact with the intersecting opposing groove, it follows that there will be a two-point contact in each groove and that the pressure of the balls upon the four points will be exactly balanced. The fulcrum member will, therefore be held against any lost motion while free to oscillate around said points of contact when said stylus is vibrated. It is needless to state that delicacy of adjustment in an instrument of the kind described is of paramount importance, and the construction shown permits such adjustment to be accomplished automatically and enables the ordinary workman to obtain results equal to those of the most highly skilled mechanic.

55 It is obvious that the relations and ad-

justments of the parts may be modified by reversal or otherwise, so long as the free-bearing points are maintained in the line of the axis of oscillation. For example the longitudinal grooves may be in the fulcrum member and the transverse ones in the members 14 and 18. I do not, therefore, wish to be limited to either construction so long as the opposing grooves are placed at such intersecting angles with respect to each other as to maintain the balls in place, and permit uniformity of contact.

70 Having thus described my invention, I claim:

1. A sound reproducer in which is combined a stylus-lever having a transverse fulcrum member provided with a plurality of not less than three grooves one of which is located between the other two and upon the opposite side of said fulcrum member, a stationary supporting member having counterpart grooves reversed respectively with respect to those of said fulcrum member so as to oppose the latter and arranged at intersecting angles thereto and bearing balls located in said opposing grooves, the points of contact between said balls and grooves forming the axis of oscillation of said fulcrum member. 76

2. A reproducer, comprising, in combination, a stylus-lever having a transverse fulcrum member provided with two grooves upon one side each formed to contact with a ball at two points only, a like groove upon the opposite side thereof substantially midway between said first named two, a stationary support having two counterpart grooves arranged at intersecting angles to those in said fulcrum member, an adjustable ball supporting member movably mounted in said supporting member the same having a groove in substantial registration with the middle groove in said fulcrum member but arranged at an intersecting angle thereto, an adjusting screw in operative connection with said adjustable ball supporting member and balls interposed between and arranged to rest in said counterpart grooves. 80

90 In testimony whereof, I have signed this specification in the presence of two subscribing witnesses, this 27th day of December, 1917.
